UNITED STATES PATENT OFFICE.

JANE R. MILLER, OF LOS ANGELES, CALIFORNIA.

DESIGN FOR A NECKLACE OR SIMILAR ARTICLE.

Application filed November 10, 1926. Serial No. 19,665. Term of patent 3½ years.

To all whom it may concern:

Be it known that I, JANE R. MILLER, a citizen of the United States of America, residing at Los Angeles, in the county of Los Angeles and State of California, have invented a new, original, and ornamental Design for a Necklace or Similar Article, of which the following is a specification, reference being had to the accompanying drawing, forming part thereof.

The figure is a front elevation of a necklace showing my new design, the detailed showing thereof being repeated on the opposite side now indicated by lines marking the outline thereof.

I claim:

The ornamental design for a necklace or similar article as shown and described.

J. R. MILLER.
